Patented June 3, 1919.

Inventor,

H. M. Johnston

By J. Edward Maybee
Atty.

UNITED STATES PATENT OFFICE.

HOWARD M. JOHNSTON, OF TORONTO, ONTARIO, CANADA, ASSIGNOR TO MASSEY-HARRIS COMPANY LIMITED, OF TORONTO, CANADA.

CANVAS CONVEYER.

1,305,608.

Specification of Letters Patent. Patented June 3, 1919.

Application filed January 16, 1919. Serial No. 271,458.

To all whom it may concern:

Be it known that I, HOWARD MILTON JOHNSTON, of the city of Toronto, in the county of York and Province of Ontario, Canada, 5 machinist, have invented certain new and useful Improvements in Canvas Conveyers, of which the following is a specification.

This invention relates particularly to the canvas conveyers used on harvester binders 10 which are usually made of approximately a suitable length and have their ends connected by straps and buckles so that the tension of the canvas may be varied as may be necessary.

15 Adjustment in this manner is so troublesome that the farmer often neglects to make adjustments when adjustments are really needed for the proper operation of the binder, and my object is to devise simple, 20 strong and reliable adjusting means which will enable an operator to make necessary adjustments rapidly and easily.

I attain my object by means of the constructions hereinafter described and illustrated in the accompanying drawings in which—

Figure 1 is a perspective view, partly broken away, showing my invention applied to an ordinary binder canvas;

30 Fig. 2 a side elevation of the lock of the device for drawing the ends of the canvas toward one another; and

Fig. 3 a perspective detail of part of the 35 socket bar of the apparatus with one of the spacers which are fitted between the parts thereof.

Fig. 4 is a perspective detail showing part of one of the canvas flaps and part of the double bar through which it is drawn.

40 In the drawings like numerals of reference indicate corresponding parts in the different figures.

1 is the conveyer canvas, which is provided with the transverse bars or flights 2 in the ordinary manner. One end of the conveyer canvas is divided to form a plurality of flaps 3, the ends of which are provided with the flat bars 4. In the preferred form the bars 4 are double being connected at 45 their ends so that in effect slotted bars are formed, the canvas passing through the slots. The other end of the conveyer canvas is provided with a socket bar provided with sockets adapted to receive the flat bars 4 with 50 canvas of the flaps folded thereon. The 55

mouth of each socket is at the back of the socket bar so that when the flat bars with the canvas folded thereon are located in the sockets, any strain on the canvas flaps tends to hold the flat bars in the sockets.

60 The socket bar is preferably constructed as follows: A flat bar 5 has the adjacent end of the canvas secured thereto. An L-shaped bar 6 is connected to the flat bar and is spaced therefrom by the spacers 7, which are 65 sufficient in number to provide a separate socket for each of the bars 4. These spacers are of such a width that a slot is formed between the depending leg of the L-shaped bar 6 and the flat bar 5 through which the canvas of the flaps 3 passes as shown. The depending leg of the L-shaped bar extends substantially level with the inner surface of the bar 5 so that the outer surface of the canvas passing over said leg is substantially in 70 the same plane as the outer surface of the bar 5. The spacers 7 are preferably formed as short rectangular tubes formed by bending up a piece of flat metal. The central spacers have integral apertured lugs 8 75 formed thereon which extend through the slot and between the two parts of the socket bar. These lugs serve for engagement with a device for drawing the ends of the conveyer together, similar lugs 9 being secured 80 to the cross bar or flight 2 located at the junction of the flaps 3 and the main part of the canvas.

85 The device for drawing the ends of the conveyer together is preferably formed as 90 shown in Figs. 1 and 2 of the drawings. 10 is a bar journaled in eyes formed on the ends of hooks 11, which are adapted to hook into the lugs 8 or 9. On this bar a flexible cord 12 is adapted to be wound as shown, the ends 95 of the cord being provided with hooks 13 adapted to be hooked into the lugs opposite the lugs with which the hooks 11 may be engaged. One end 16 of the bar 10 is squared for engagement with a wrench. At 100 the same end of the bar, a hook 14 is provided adapted to slide on the adjacent hook 11. This hook has a keyhole slot 15 formed in its end. In part of this keyhole slot the squared end 16 may turn freely, but the 105 other part of the slot is adapted to engage the sides of the squared end as shown in Fig. 1 to hold the bar 10 from turning.

110 The operation of the device is as follows: Assuming the conveyer is to be adjusted in

length, the device for drawing the ends together is placed in position as shown in Fig. 1, the lock 14 released and the bar 10 rotated until the flat bars 5 with the ends of the conveyer flaps wrapped thereon can be pulled out of the sockets in the socket bar. The flat bars are then turned until the canvas lies flat between them as shown in Fig. 4 and then slid along to either lengthen or 10 shorten the flaps 3 as may be necessary and then given a half turn and replaced in the sockets. The bar 10 is then released and allowed to rotate until the flaps again take all the strain, when the device may be removed. It will be understood, of course, 15 that there is always sufficient spring in the conveyer to permit of the temporary overtightening described being readily effected at any time without damage to the conveyer. The whole operation takes but a very few minutes, and when the flat bars with the canvas wrapped around them are engaged in the sockets in the socket bars, the connection 20 between the conveyer ends will be absolutely secure, owing to the fact that the width of the sockets is only sufficient for the bars to enter flatwise so that they cannot rotate in the sockets. At the left hand side of the drawing in Fig. 1, the flat 25 bar 2 has been unrolled a few more turns than the bars connected with the other flaps. When the device is in use, this bar will be rotated to shorten its flap the same length as the others and will then occupy the position in its own socket.

What I claim as my invention is:

1. A conveyer canvas having a flat bar connected therewith adjacent one end on 40 which the canvas may be rolled, and a socket bar secured to the other end of the canvas adapted to receive the flat bar with the canvas rolled thereon, the mouth of the socket being at the back of the bar.

2. A conveyer canvas having a flat bar 45 connected therewith adjacent one end on which the canvas may be rolled, and a socket bar secured to the other end of the canvas adapted to receive the flat bar with the can-

vas rolled thereon, the mouth of the socket being at the back of the bar, the socket bar 50 also having a slot formed along its forward side through which the end of the canvas secured to the flat bar passes.

3. A conveyer canvas having a flat bar connected therewith adjacent one end on 55 which the canvas may be rolled, and a socket bar secured to the other end of the canvas adapted to receive the flat bar with the canvas rolled thereon, the mouth of the socket being at the back of the bar, in combination 60 with means connected with the flat bar and the socket bar for drawing the same toward one another.

4. A device constructed according to claim 1 in which the first mentioned end of the 65 canvas is divided to form a plurality of flaps, each provided with a separate bar, and in which the sides of the socket bar are connected by spacers to form a separate socket for each flat bar and the canvas wound 70 thereon.

5. A specific construction of the socket bar according to claim 1 in which the socket 75 bar is formed of a flat bar to which the adjacent end of the canvas is connected and an L-shaped bar connected to the flat bar and spaced by spacers so as to leave a space between the two bars at the forward side forming a slot.

6. A specific construction of the socket 80 bar according to claim 1 in which the socket bar is formed of a flat bar to which the adjacent end of the canvas is connected and an L-shaped bar connected to the flat bar and spaced by spacers so as to leave a space 85 between the two bars at the forward side forming a slot, apertured lugs being formed on the spacers projecting through said slot and serving for the attachment of a device for drawing the ends of the canvas together.

Signed at the city of Toronto, this second 90 day of January, 1919.

HOWARD M. JOHNSTON.
